UNITED STATES PATENT OFFICE.

ROBERT C. SHERRARD, OF CHICAGO, ILLINOIS, ASSIGNOR TO UNITED ORDER OF FORESTERS, OF CHICAGO, ILLINOIS, A CORPORATION.

DESIGN FOR A BADGE.

No. 38,490.

Specification for Design.

Patented March 26, 1907.

Application filed January 31, 1907. Serial No. 355,157. Term of patent 3½ years.

To all whom it may concern:

Be it known that I, ROBERT C. SHERRARD, a citizen of the United States, residing at Chicago, in the county of Cook and State of Illinois, have invented a new, original, and ornamental Design for a Badge, of which the following is a specification, reference being had to the accompanying drawing, forming part thereof.

The figure is a plan view of a badge, showing my design.

What I claim is—

The ornamental design for a badge as shown.

ROBERT C. SHERRARD.
